Primary Examiner — Cynthia R Underwood*(74) Attorney, Agent, or Firm* — Fideli Law PLLC; Qiang Li(57) **CLAIM**

The ornamental design for an anti-theft nut as shown and described.

DESCRIPTION

FIG. 1 is a first perspective view of the design;
FIG. 2 is a second perspective view of the design;
FIG. 3 is a front view of the design;
FIG. 4 is a left view of the design;
FIG. 5 is a right view of the design;
FIG. 6 is a rear view of the design;
FIG. 7 is a top view of the design; and,
FIG. 8 is a bottom view of the design.

1 Claim, 8 Drawing Sheets(56)
